DESIGN FOR A TIRE

William P. MacKusick, Akron, Ohio, assignor to Wingfoot Corporation, Wilmington, Del., a corporation of Delaware

Application April 24, 1936, Serial No. 62,286

Term of patent 14 years

To all whom it may concern:

Be it known that I, William P. MacKusick, a citizen of the United States, residing at Akron, in the county of Summit and State of Ohio, have invented a new, original, and ornamental Design for a Tire, of which the following is a specification, reference being had to the accompanying drawing, forming part thereof.

Fig. 1 is a perspective view of a tire, a section thereof being illustrated in full lines, showing my design;

Fig. 2 is a cross-section on line II—II of Fig. 1; and

Fig. 3 is a fragmentary cross-sectional view taken on line III—III of Fig. 1.

I claim:

The ornamental design for a tire, as shown.

WILLIAM P. MACKUSICK.
